UNITED STATES PATENT OFFICE.

BERRY A. BROWN, SR., OF FRANKLIN, OHIO.

DESIGN FOR A TROUSERS-GUARD.

46,661.

Specification for Design.

Patented Nov. 24, 1914.

Application filed July 1, 1914. Serial No. 848,490. Term of patent 7 years.

To all whom it may concern:

Be it known that I, BERRY A. BROWN, Sr., a citizen of the United States, residing at Franklin, in the county of Warren and State of Ohio, have invented a new, original, and ornamental Design for Trousers-Guards, of which the following is a specification, reference being had to the accompanying drawings, forming a part thereof.

Figure 1 is a perspective view of my trousers guard, and Fig. 2 is a plan view of the same.

I claim:

The ornamental design for a trousers guard, as shown.

BERRY A. BROWN, Sr.

In the presence of—

P. H. RUE,

B. A. BROWN, Jr.
